(57) **CLAIM**

The ornamental design for a window treatment as shown and described.

DESCRIPTION

FIG. 1 is a perspective view of a window treatment showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment thereof;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken lines illustrate portions of the window treatment that form no part of the claimed design.

The break lines shown in FIGS. 8-12 symbolize breaks in the length of the article in which the claimed design is embodied. The appearance of any portion of the article between the break lines forms no part of the claimed design.

1 Claim, 6 Drawing Sheets
